UNITED STATES PATENT OFFICE.

LAWRENCE Y. SPEAR, OF GREENPORT, NEW YORK, ASSIGNOR TO ELECTRIC BOAT COMPANY, OF NEW YORK, N. Y., A CORPORATION OF NEW JERSEY.

BUOYANCY-REGULATING APPARATUS FOR SUBMARINE BOATS.

SPECIFICATION forming part of Letters Patent No. 772,970, dated October 25, 1904.

Application filed November 12, 1903. Serial No. 180,811. (No model.)

To all whom it may concern:

Be it known that I, LAWRENCE Y. SPEAR, a citizen of the United States, residing at Greenport, in the county of Suffolk and State of New York, have invented certain Improvements in Buoyancy-Regulating Apparatus for Submarine Boats, of which the following is a specification.

This invention relates to buoyancy-regulating devices applicable to all classes of submarine boats, but especially to such types of these boats as have normally, when navigating below the surface of the water, a certain amount of reserve or surplus buoyancy residing, wholly or in part, in the conning-tower or sighting-hood of the boat, which projects above the hull of the latter.

The object of the invention is to provide means whereby the reserve buoyancy of the boat or vessel may be varied at will, means for visually indicating such buoyancy, and means enabling the operator to effect the initial regulation of the reserve buoyancy in any state or condition of wind and water and to maintain such reserve despite changes in the specific gravity of the water of flotation.

In the accompanying drawings, which illustrate an embodiment of the invention, it has been found convenient to illustrate separately some of the component parts of the invention installed in the boat, as most conducive to clearness; but all parts thereof coöperate and form a part of the same apparatus.

In the drawings, Figure 1 is a transverse section of a submarine boat at line α' in Fig. 2, and Fig. 2 is a vertical longitudinal section of same at line α^2 in Fig. 1. For convenience of illustration, however, the gage device is shown in Fig. 2 on the side of the conning-tower opposite to that seen in Fig. 1. Fig. 3 is a transverse section of a part of the boat-hull, showing the internal mechanism in elevation as seen from the right in Fig. 2. Fig. 4 is a transverse section of the boat on a larger scale than the principal views and showing the hydrometer-gage, and Fig. 4^a is a detail cross-section at α^4 . Figs. 5, 6, and 7 are sectional

detail views of the multiple-way cock seen in Figs. 2 and 3. Fig. 5 is in axial section, and Figs. 6 and 7 are respectively transverse sections at lines α^6 and α^7 in Fig. 5.

Referring primarily to Figs. 1 and 2, 1 designates the hull or shell of a submarine boat, and 2 the conning-tower thereof. A, B, C, and D are adjusting water-tanks in the boat. For convenience merely, these water-tanks are shown as arranged in two sets of four each and disposed one series at each side of the center line of the boat. If other arrangements permitted, they might, however, be arranged along the center line of the vessel or boat. The number and capacity of these tanks is not limited absolutely; but, generally speaking, their total capacity should be at least double the maximum reserve buoyancy which it is desired to employ, and the number should be such as to provide a convenient unit of capacity for each—as, for example, one hundred pounds of salt water for each. As shown in the drawings, the tanks of each set (see Fig. 2) are connected in series by water-pipes 3, extending from near the bottom of one tank to the top of that next adjacent, and in each pipe 3 is a stop-valve 4—that is to say, a pipe 3 connects the bottom of tank A with the top of tank B and a pipe 4 connects the bottom of tank B with the top of tank C. The last tank D of the set is connected by a pipe 5 with the sea. A pipe 6 supplies compressed air from a tank (not shown, but found on all submarine boats) through branches 7 to the tops of the several tanks, the supply of air being controlled by stop valves or cocks 8 in the several branches. Each tank will have a vent-cock 9, gage-cocks 10, and a drain-cock 11.

Beginning with the tank D, it is possible with these connections to fill or empty any number of tanks in the set. For example, if it be desired to fill tanks D and C the valves 4 and cocks 9 of these tanks are opened and the tanks fill from the sea, after which the valves and cocks are closed. If it be desired to empty both of these tanks, the valves 4 pertaining to both tanks are opened and the

valve 8 pertaining to the tank C opened. The compressed air enters the tank C and blows out the water from both tanks in series.

The tanks are herein shown for convenience 5 of illustration as separate or individual, but obviously a single tank properly partitioned would serve the same purpose. Where the tanks are disposed in two sets, one set at each side of the center line of the boat, it 10 will be necessary, in order to preserve the equilibrium of the boat, to fill and empty the corresponding tanks at opposite sides at the same time.

Auxiliary to and forming a part of the means 15 for regulating the reserve buoyancy last described is a means for effecting a fine adjustment between the weight and buoyancy of the boat when these are substantially equal and at the same time confining the means employed to a small and reliable device capable 20 of being manually operated. This device is seen in Figs. 2 and 3 and details thereof in Figs. 5, 6, and 7. It is shown so disposed as to operate in connection with the tank A of 25 the series. E is a special multiple-way valve, the characteristic features of which will be hereinafter fully described. A water-pipe 12 connects the bottom of the tank A with the sea through the valve E, and a branch 30 13 from the main air-pipe 6 leads to the top of the tank A through the valve E. In Figs. 5, 6, and 7 the casing 14 of the valve E has set in it the branches of the water-pipe 12, Fig. 7, and the branches of the air-pipe 13, 35 Fig. 6, and these figures show the plug 15 of the valve provided with a water-chamber 16 and an air-chamber 17. These chambers are separated and distinct, having no communication with each other. In the plug 15 are 40 two air-ports 18, Fig. 6, which may be put into register with the respective branches of the air-pipe 13 by turning the plug, and thus connect the main air-pipe 6 with the tank A through the valve E, and in the plug are also 45 ports 19, Fig. 7, which may be put into register with the respective branches of the water-pipe 12, and thus connect the tank A with the sea for filling or blowing out. There are three water-ports 19 in the plug and two air- 50 ports 18 therein, and there is an air-port 20 in the valve-casing 14 opening to the interior of the boat. On the packet-stem of the plug 15 is a hand-wheel 21 for rotating the plug.

As shown in Figs. 6 and 7, the plug 15 stands 55 in a position to close all of its ports and cut off both the air-pipe 13 and water-pipe 12. Now if the plug be turned to the right, as seen in these figures, until the ports in the plug coincide with the respective air and water pipes 60 the tank A will be opened to the sea and to the compressed air and the latter will blow the water out of the tank. If now the plug be turned to the left till the ports are in proper register, the air will be cut off from 65 the compressed-air tank and a way opened

for the flow of air from the tank A through the port 20 to the interior of the boat and at the same time the tank A will be opened to the sea for filling by putting two of the three ports 19 into proper register with the branches 70 of the pipe 12.

In order to secure a fine control, it is desirable that the ports shall be brought into register slowly and gradually, and this gradual opening of the ways is attained by the circular form of the ports in the plug and casing 75 of the valve.

The utility of the device will be apparent from the above description, it being understood that the operator will have before him 80 a depth-gage to note the extent to which the boat rises and sinks in the water. This combination described may be employed to fill or blow out the adjustment-tanks at any desired rate, as already explained, and also to enable 85 the operator to totally destroy the buoyancy of the vessel or boat, and thus drop the same gradually, when not under way, to any desired depth or to the bottom.

The buoyancy-gage used in connection with 90 devices described above is illustrated in Figs. 1 and 2, being mounted on the conning-tower 2.

An upright glass gage-tube 22 is connected at its respective upper and lower ends by tubes 23 with the upper and lower ends of a chamber in an expansion vessel 24, exterior to the conning-tower and secured rigidly thereto by preference. In its top the expansion vessel is provided with a small aperture 25 for the escape of air, and at its bottom it is connected 100 by a pipe 26 with the water of flotation at the bottom of the boat or vessel or a good distance below the surface. It is convenient to run the pipe 26 down inside of the vessel, as seen in Fig. 1; but the special arrangement 105 of this pipe is not important to the invention. Adjacent to the glass gage-tube 22 is a plate having marked on it two scales 27 and 28, one graduated for fresh water and the other for normal salt water. These scales read 110 from the top downward and show the displacement of the conning-tower from the top, as the zero-point, in pounds of water, salt or fresh, as the case may be.

The pipe 26 will be of relatively small diameter and at its lower end it will be preferably connected with the water of flotation at the lowest available point of the boat and in the wake of the center of gravity when the boat is submerged. When the boat is trimmed down ready for diving, with the water-line at W, the height of the water in the gage-tube 22, as read on the scale, gives at once the displacement of the emerged portion 120 of the conning-tower, or, in other words, the 125 reserve buoyancy.

The chamber in the expansion-vessel 24 enables the observer to get the true water-level 130 in the gage in rough weather or when the water is disturbed and the sea choppy. This

is due obviously to the fact that the gage-tube is connected with the chamber in the vessel 24, and the said chamber is connected, through the tube 26, with the undisturbed water at some distance below the surface. Although there may be rapid fluctuations in the surface-level exterior to and about the conning-tower due to superficial wave formations, the fluctuation within the vessel 24 will 5 be slight and relatively slow, while the gradual sinking of the vessel will be clearly visible and easily noted on the gage.

The means used in connection with the devices already described for determining the 15 salinity of the water of flotation and its relation to the reserve buoyancy is illustrated in Figs. 4 and 4^a. For the sake of clearness other features are omitted from Fig. 4.

29 is an upright closed cylinder connected 20 at its top with the sea or water of flotation by a pipe 30, controlled by a cock 31. The cylinder has drain-cocks 32.

Within the cylinder 29 is a float 33, provided with circumferential vanes 34 to prevent or reduce vertical vibration. This float 25 has an upwardly-extending stem 35, to which is secured a double-pointed indicator 36, one point of which traverses a fixed scale 37, marked on the upright plate or bar 38, and 30 the other point traverses an adjustable scale 39 on the said bar.

The hydrometer is designed to operate in the usual way in liquid of specific gravity varying between that of fresh water and ordinary sea-water. Thus in fresh water the float 35 will be at the bottom of the cylinder 29 and in salt water it will be at the top of the latter. The fixed scale 37 is graduated to indicate the difference in displacement of the 40 boat or vessel in salt and fresh water. The adjustable scale 39 has its zero-point at the middle of its length and the scale is at least of sufficient length to read, on either side of zero, a change in displacement equal to the 45 total capacity of the adjusting-tanks, and the unit on the divisions of the scale is the capacity of a single one of said tanks.

The scale 39 may be mounted adjustably in any convenient way. As herein shown, the 50 folded graduated plate has in it a slot through which passes a securing-screw 40, which clamps the scale fast when set.

The operation is as follows: When it is desired to submerge the boat or vessel, the valve 55 31 and the upper drain-cock 32 are opened and the cylinder 29 is filled up to the level of the upper cock 32. The fixed scale 37 will now show at a glance the total weight required in the boat in order to produce diving trim. 60 The adjustable scale 39 is now shifted until its zero-mark registers exactly with the point on the indicator 36, and said scale is then clamped fast by the securing-screw 40. The cylinder 29 is now drained by opening the 65 cocks 32, and at any subsequent time the

change in displacement in the boat due to a change in specific gravity of the water of flotation may be ascertained by again filling the cylinder 29 with water of flotation and reading the indication made by the point of the 70 indicator 36 on the adjustable scale 39, which after such reading is again set with its zero at the point on the indicator and the cylinder 29 again emptied.

As a whole the object of this invention is, 75 first, to enable the operator or person commanding the vessel or boat to make the initial regulation of surplus buoyancy in any state or condition of wind and water, and, second, to enable him to maintain the initial reserve buoyancy despite changes in the specific gravity of the water of flotation, such as may occur in the movement of the boat from place to place and from changes in the wind and currents. 80

The operation of the device taken as a whole is as follows:

First, in ordinarily smooth weather. In this case one-half of the adjusting-tanks are filled 90 with water and then the vessel is submerged by known means until the desired amount of reserve buoyancy is shown on the buoyancy-gage 22, and at the same time the hydrometer-cylinder 29 is filled, as described above, and the adjustable gage 39 set, also as above described, to the pointer or indicator 36. The boat may now be submerged and at any desirable time interval hydrometer readings may be taken from the adjustable scale 29, which will give at once the change in weight required 100 in order to maintain the original reserve buoyancy. Such change can then be made with accuracy by filling or blowing out the water from one or more of the adjusting-tanks. 105

Second, in very rough weather. This supposes a condition of the water of flotation in which the buoyancy-gage cannot well be read with sufficient accuracy. In this case such a number of the adjusting-tanks are filled that the total amount of water in them shall be 110 equal to one-half of their total capacity plus the amount of the reserve buoyancy desired, and at the same time a hydrometer reading is taken from the adjustable scale 39, as explained. The boat is then submerged by 115 known means until her buoyancy is completely destroyed and she begins to sink, whereupon a sufficient number of adjusting-tanks are blown out to give the desired amount of reserve buoyancy, which will leave the tanks 120 half full, so that the operation of changing weight to correspond to changes in the specific gravity of the water of flotation may be carried out at any desired intervals of time, as above explained. 125

In the above description it has been assumed that the conning-tower is placed at the center of buoyancy of the boat when submerged and that the adjusting-tanks are grouped symmetrically about the conning-tower in order 130

that the various operations described may not alter the longitudinal trim of the boat. However, the invention is not limited to this disposition of the parts. For example, the adjusting-tanks may be so located that a capacity thereof at least equal to the maximum reserve buoyancy desired will have its center practically coincident with the center of the conning-tower, while at least an equal number shall be grouped at the same distance on the other side of the center of buoyancy of the boat and double the number shall be grouped at the said center of buoyancy in order that changes in weight made to correct changes in specific gravity of the water of flotation may have no effect on the longitudinal trim of the boat. In such a disposition when the boat is finally submerged with the normal reserve buoyancy the middle group of tanks would be full and the end groups thereof empty.

Having thus described my invention, I claim—

1. A submarine boat having means for regulating and maintaining the reserve or surplus buoyancy of the boat, said means comprising a plurality of connected adjusting-tanks of known capacity, means for filling one or more of said tanks from water of flotation, means for blowing out the water from one or more of said tanks, and gages, actuated by a hydrometer, showing the weight required to put the boat in diving trim and the changes in displacement due to differences in the specific gravity of the water of flotation.

2. A submarine boat having means for regulating and maintaining the reserve buoyancy of the boat, said means comprising a plurality of adjusting-tanks of equal and known capacity, means for blowing the water out of any one or more of such tanks, water-pipes connecting the end tank of the series with the water of flotation, and connecting the top of one tank with the bottom of the next adjacent, a buoyancy-gage connected with the water at the bottom of the boat and showing the reserve buoyancy when the boat is in diving trim, and a hydrometer showing the displacement in the water of flotation.

3. A submarine boat having a plurality of adjusting water-tanks disposed in series, pipes connecting said tanks, a pipe connecting the bottom of the end tank of the series with the water of flotation, means for expelling the water from the tanks, means for determining

the displacement of the boat, and means for determining the reserve buoyancy of the boat, the said tanks being of equal and known capacity.

4. A submarine boat, having means for regulating the reserve buoyancy of the boat, comprising a plurality of adjusting water-tanks, and means for filling and emptying said tanks, of a special means for filling and emptying one of said tanks, said means comprising the pipe 12 connecting one of said tanks with the sea, an air-pipe 13 for supplying compressed air to the said tank for blowing the water therefrom, and a multiple-way valve E, controlling simultaneously the flow of both air and water to and from said tank.

5. A submarine boat having means for taking in and blowing out water to regulate its reserve buoyancy, and having also a buoyancy-gage device comprising an upright, transparent gage-tube 22 inside of its conning-tower, an expansion vessel 24, exterior to the tower, said vessel having a small aperture in its top, tubes connecting the upper and lower ends of the gage-tube with the said expansion vessel, a pipe connecting the bottom of said vessel with the water of flotation at the bottom of the submarine boat, and scales for fresh and salt water adjacent to the gage-tube, said scales having graduations numbered downward and showing the reserve buoyancy in the tower.

6. A submarine boat having means for taking in and blowing out water to regulate its reserve buoyancy, and having also a hydrometer-gage device comprising an upright cylinder 29, a cock-controlled pipe connecting said cylinder with the water of flotation, drain-cocks on said cylinder, a hydrometer-float 33 in said cylinder, the upright stem of said float provided with a pointer or indicator 36, a fixed scale 37, over which said indicator plays, said scale being graduated to show the displacement of the boat, and an adjustable scale 39, also traversed by said indicator and having its zero-mark at the middle of its length, substantially as and for the purpose set forth.

In witness whereof I have hereunto signed my name, this 4th day of November, 1903, in the presence of two subscribing witnesses.

LAWRENCE Y. SPEAR.
